UNITED STATES PATENT OFFICE.

CHARLES M. KING, OF DOWNEYVILLE, CALIFORNIA.

ANVIL ATTACHMENT.

SPECIFICATION forming part of Letters Patent No. 426,280, dated April 22, 1890.

Application filed December 27, 1889. Serial No. 335,158. (No model.)

To all whom it may concern:

Be it known that I, CHARLES M. KING, of Downieville, in the county of Sierra and State of California, have invented a new and 5 Improved Anvil Attachment, of which the following is a full, clear, and exact description.

My invention is adapted to be attached to an ordinary blacksmith's anvil; and the object of my invention is to provide means whereby metal may be quickly and easily 10 bent and cut off upon the anvil.

Heretofore when a blacksmith has had occasion to bend a piece of metal it has been 15 the practice to take the metal in a heated condition to an ordinary vise and bend it in the vise, or have an assistant hold a bending-piece upon the anvil and bend the metal over that; but my invention obviates this 20 difficulty by providing means whereby the blacksmith may bend and cut off the metal upon the anvil without the help of an assistant.

To this end my invention consists in a 25 swinging arm provided with a grip and actuated by a chain or cord connected with a treadle-lever and attached to the anvil-block, so that by depressing the lever the grip will be swung upon the end of the anvil in position to hold a piece of metal thereon. This 30 construction will be hereinafter fully described, and specifically pointed out in the claims.

Reference is to be had to the accompanying 35 drawings, forming a part of this specification, in which similar letters of reference indicate corresponding parts in all the figures.

Figure 1 is a side elevation of an anvil and 40 block provided with my invention, with a portion of the anvil-block in section to show the manner in which the invention is attached, and with the grip and swinging arm depending from the anvil-block. Fig. 2 is a 45 front elevation of the same, but showing a grip without a hardy and clasping the end of the anvil, ready for use. Fig. 3 is an enlarged detail showing the manner in which the swinging arm is held and pivoted to the anvil-block, and Fig. 4 is an enlarged detail of the 50 pivot end of the swinging arm.

The anvil A and anvil-block B are of the usual construction, except that the anvil-block is hollowed out upon each side near the bottom, so that the lever C, which is attached

thereto, will not project beyond the sides of 55 the anvil-block and interfere with the blacksmith's work.

The U-shaped lever C is pivoted to the sides of the anvil-block B by the pin a, and is provided with a suitable treadle b, so that 60 it may be easily actuated by the foot of the blacksmith. A chain d is attached by one end to the lever C and by the other end to the end of an arm D, pivoted in a bracket E, 65 attached to the anvil-block.

The arm D is provided at its free end with a grip e, which is of a rectangular shape and is large enough to clasp the end f of the anvil and to admit a fair-sized strip or bar of metal between it and the face of the anvil; 70 and the other end of the arm is formed into a disk g, which is pivoted between the projecting sides of the bracket E by the bosses or strips g', and the disk is provided upon its periphery with a groove, as shown in Fig. 75 2, to receive the chain or cord d.

The bracket E is provided with flanges i, having screw-holes therein, by means of which it is attached to the anvil-block B. The bracket E is also provided upon each side 80 with a vertical slot j, enlarged and circular at the upper end, which circular ends receive the bosses or strips g' by which the arm D is pivoted to the lug, and from the bosses g' project axially the pins h. The arm D will be 85 capable of a vertical movement in the bracket E a distance corresponding to the length of the slots j.

The strips g' are attached to the sides of the disk g, or may be made integral with it 90 and project therefrom so that they will enter the slot j of the bracket E and turn in the upper enlarged circular part of the slot. The strips are so attached to the disk that when the arm D is in a vertical position and the 95 treadle-lever C is depressed they will slide into the lower part of the slot j and will be retained by the sides of the slot so that the arm D cannot be tipped down.

Springs k are attached to the anvil-block 100 B and extend outwardly along the sides of the bracket E and underneath the ends of the pins h, which project from the bosses or strips g' and press said pins and strips to the top of the slot j of the bracket E, so that 105 when the arm D is in a vertical position, with the grip e clasping the end f of the anvil, the springs k acting upon the pin h, strips

g', and arm D will hold the grip in an elevated position, as shown in Fig. 2, so that there will be a space between the top of the grip and the face of the anvil, in which metal 5 may be inserted and held, as hereinafter described.

The chain *d* is attached to the lever C directly underneath the bracket E, and the other end of the chain is attached to the disk *g* of 10 the arm D, near the inner side of the arm when it is in a vertical position, so that when the arm is tipped down, as shown in Fig. 1, the chain *d* will be wound nearly around the disk *g*, as indicated by the dotted lines in the same 15 figure.

When the foot is placed upon the treadle *b*, the lever C is depressed, the chain *d* is tightened, and this, acting upon the disk *g*, turns the disk upon the strips *g'* in the end 20 of the slot *j* and raises the arm D, so that the grip *e* will clasp the end *f* of the anvil with the grip in an elevated position, with a space between the top of the grip and the face of the anvil. By increasing the pressure 25 upon the treadle *b* the pins *h*, which bear upon the springs *k*, will depress the springs, the strips *g'* will slide downwardly in the slots *j* of the lug E, and the arm D will drop vertically, thus bringing the grip *e* firmly upon any 30 metal which may be between the grip and the anvil, or, if there is no metal there, the grip will be forced down to a solid bearing upon the anvil, so that the hardy *l* may be used in the usual manner. By removing the 35 pressure the springs *k* will lift the arm D and grip *e*, and the action may be repeated as often as necessary.

To bend a piece of metal, the blacksmith places the end of the piece to be bent between 40 the face of the anvil and the grip *e*. By increasing the pressure upon the treadle *b* the grip *e* will be forced down upon the metal, and it will be held as in a vise, so that the metal may be bent over the end of the anvil 45 *f* by a few blows from the blacksmith's hammer.

The grip *e* may be provided at the top with a hardy *l*, so that by forcing the top of the grip *e* upon the face of the anvil A to make a 50 solid bearing a piece of metal may be cut off upon the hardy *l* in the usual manner.

This invention is especially valuable to the blacksmith in fitting horseshoes. By pressing upon the treadle *b* the grip *e* and hardy *l* will 55 be thrown into position in the manner described for cutting the heels of the shoe, and by removing some of the pressure the springs *k* will raise the grip *e*, so that the shoe may be held between the grip and anvil and turned 60 into the required shape.

When the grip *e* or hardy *l* is not in use, the arm D is tipped down into the position shown in Fig. 2.

Having thus described my invention, what 65 I claim as new, and desire to secure by Letters Patent, is—

1. The combination, with an anvil and anvil-block, of a vertically-swinging arm pivotally attached to the anvil-block, having at one end a grip adapted to clasp the end of the anvil, and means for actuating said arm, substantially as described, and for the purpose set forth. 70

2. The combination, with an anvil and anvil-block, of a vertically-swinging arm pivotally attached to the anvil-block, having at one end a grip adapted to clasp the end of the anvil, and having the other end connected by a chain or cord with a suitable lever for actuating said arm, substantially as described, 80 and for the purpose set forth. 75

3. The combination, with an anvil and anvil-block, of a vertically-swinging arm pivotally attached to the anvil-block, having one end provided with a grip adapted to clasp the end of the anvil and a hardy for cutting off metal, and the other end connected by a chain or cord with suitable treadle-lever for actuating said arm, substantially as described. 85

4. The combination, with an anvil and anvil-block, of a vertically-swinging arm pivotally attached to the anvil-block, having one end provided with a grip adapted to clasp the end of the anvil, the other end connected with a suitable lever for actuating said arm, 95 and a spring for raising said arm to the top of its bearings, substantially as described. 90

5. The combination, with an anvil and anvil-block, of a slotted bracket, an arm pivoted in said bracket having one end adapted to 100 clasp the end of the anvil, a treadle-lever, and connections between the arm and lever, substantially as described.

6. The combination, with an anvil and anvil-block and a bracket provided in its sides 105 with slots having circular upper ends, of an arm provided with a grip at one end and with a disk having flat bosses at the other end, a treadle-lever, and a chain attached to the lever and the disk, substantially as described. 110

7. The combination, with an anvil and anvil-block and a bracket provided in its sides with slots having circular upper ends, of an arm provided with a grip at one end and with a disk having flat bosses at the other end, a 115 treadle-lever, a chain attached to the lever and the disk, and springs engaging said bosses, substantially as described.

8. The combination, with an anvil and anvil-block, of the arm D, having grip *e*, disk *g*, with strips *g'* and pins *h*, bracket E, having slots *j*, chain and cord *d*, and lever C, substantially as described. 120

9. The combination, with an anvil and anvil-block, of the arm D, having grip *e*, hardy *l*, disk *g*, with strips *g'* and pins *h*, bracket E, having slots *j*, chain or cord *d*, and lever C, substantially as described. 125
